Specification for Design.

Patented Mar. 2, 1920.

Application filed June 9, 1919. Serial No. 302,991. Term of patent $3\frac{1}{2}$ years.

To all whom it may concern:

Be it known that I, ALICE H. FLANDERS, a citizen of the United States, residing at Chicago, in the county of Cook and State of Illinois, have invented a new, original, and ornamental Design for a Woman's Blouse, (No. 628,) of which the following is a specification, reference being had to the accompanying drawing, forming part thereof.

Fig. 2 is a similar view of the front side of the same.

I claim:

The ornamental design for a woman's blouse, as shown.

ALICE H. FLANDERS.
